UNITED STATES PATENT OFFICE.

JOHN WILLIAM HARM, OF EL PASO, TEXAS.

TUBULAR PLATE-CASTING BOX.

1,174,978.

Specification of Letters Patent. Patented Mar. 14, 1916.

Application filed July 21, 1915. Serial No. 41,133.

To all whom it may concern:

Be it known that I, JOHN WILLIAM HARM, citizen of the United States, residing at El Paso, in the county of El Paso and State of Texas, have invented certain new and useful Improvements in Tubular Plate-Casting Boxes, of which the following is a specification, reference being had to the accompanying drawings.

10 This invention relates to certain improvements in tubular stereotype plate casting boxes and it is an object of the invention to provide a device of this general character having novel and improved means whereby 15 the cast plate is automatically raised relatively to the core as the core is swung from operative position within the cope.

The invention consists in the details of construction and in the combination and 20 arrangement of the several parts of my improved tubular casting boxes whereby certain important advantages are attained and the device is rendered simpler, less expensive and otherwise more convenient and 25 advantageous for use, all as will be hereinafter more fully set forth.

The novel features of the invention will be carefully defined in the appended claims.

In order that my invention may be the 30 better understood, I will now proceed to describe the same with reference to the accompanying drawings, wherein—

Figure 1 is a view in side elevation partly in dotted lines and partly in full lines of a 35 tubular plate cast box having an embodiment of my invention applied thereto. Fig. 2 is a view similar to Fig. 1 except certain of the parts are disclosed in a different adjustment. Fig. 3 is a view in front elevation partly in dotted lines and partly in full 40 lines of my invention as herein set forth. Fig. 4 is a fragmentary view in elevation of the pivoted extremity of the core of the cast box illustrating certain details of my invention as herein embodied, the head ring being indicated by dotted lines. Fig. 5 is a 45 view in perspective detached of one of the operating arms herein employed.

As disclosed in the accompanying drawings, A denotes a tubular plate cast box of 50 any ordinary or preferred construction and herein disclosed as the well known "duplex type," and wherein is employed the vertically swinging core C coacting in a well known manner with the cope B.

Slidably engaged with the core C is the

head ring H and operatively engaged with said head ring at diametrically opposed points are the arms 1 depending from the ring H and having their lower portions provided with the inwardly disposed lugs 2, traveling within the longitudinally disposed grooves 3 produced in the core C, and the lower longitudinal marginal portions of the grooves 3 are defined by the outstanding 65 flanges 4, between which the arms 1 travel, said flanges serving as an additional guiding means for the arms 1.

The upper extremities of the arms 1 are provided with the heads 5 adapted to be positioned within the recesses 6 produced in the periphery of the ring H at diametrically opposed points, said head and recesses being of such formation as to afford an effective connection, and in order to maintain the 70 arms 1 against displacement relative to the ring H, I find it of advantage to employ the threaded members 7 engageable with both members the ring H and the heads 5.

Operatively supported by the base 8 of 80 the cast box and at a predetermined point at opposite sides of the core C, are the plates 9 provided with cam slots 10 in which are positioned the rollers 11, mounted upon the stub shafts 12, removably engaged with the 85 arms 1 and I prefer to provide said roller 11 with the flanges 14 adapted to engage the inner faces of the plates 9.

It is to be observed that the slots 10 are so arranged as to automatically cause the head 90 ring H to move upwardly relative to the core C as the core swings from vertical position so that the cast plate will be projected a sufficient distance beyond the outer or free extremity of the core C to permit said 95 cast plate to be readily engaged by the operator and entirely removed from the core. It will also be perceived that upon the core C being turned to a vertical position in order to be properly positioned within the 100 cope B that the head ring H will be automatically returned to its operative position.

From the foregoing description, it is thought to be obvious that tubular plate casting boxes constructed in accordance with my 105 invention is of an extremely simple and comparatively inexpensive nature and is particularly well adapted for use by reason of the convenience and facility with which it may be assembled, and it will also be obvious that my invention is susceptible of 110 some change and modification without ma-

terial departure from the principles and spirit thereof and for this reason I do not wish to be understood as limiting myself to the precise arrangement and formation of the several parts herein shown in carrying out my invention in practice.

I claim:

1. In combination with a tubular plate cast box including a swinging core, a head ring slidably mounted upon said core and means for moving said ring longitudinally of the core upon swinging movement of the core.
2. In combination with a tubular plate cast box including a movable core, a head ring slidably mounted upon the core and means for imparting separate movement to the head ring upon the core in unison with the movement of the core.
3. In combination with a tubular plate cast box including a movable core, means for imparting separate movement to the cast plate upon the core in unison with the movement of the core into an inoperative adjustment.
4. In combination with a tubular plate cast box including a swinging core, a head ring slidably mounted upon the core and stationary means coacting with the head ring for imparting movement thereto longitudinally of the core during the swinging movement of the core.

Copies of this patent may be obtained for five cents each, by addressing the "Commissioner of Patents, Washington, D. C."

5. In combination with a tubular plate cast box including a swinging core, a head ring slidably mounted thereon, and a cam action separate from the core and coacting with the head ring for imparting movement to the ring longitudinally of the core during the swinging movement of the core.

6. In combination with a tubular plate cast box including a swinging core, a head ring slidably mounted thereon, an arm engageable with the ring, and a cam member supported independently of the core and coacting with the arm to impart movement to the ring longitudinally of the core during the swinging movement of the core.

7. In combination with a tubular plate cast box including a swinging core, a head ring slidably mounted thereon, an arm engageable with the ring, a plate positioned adjacent the core and provided with a cam slot and a member carried by the arm and disposed within the slot, said cam slot being so formed as to impart movement to the head ring longitudinally of the core during the swinging movement of the core.

In testimony whereof I hereunto affix my signature in the presence of two witnesses.

JOHN WILLIAM HARM.
